UNITED STATES PATENT OFFICE.

LAWRENCE WHITEMAN, OF SHINNSTON, WEST VIRGINIA.

FLOATLESS CARBURETOR.

Application filed August 18, 1922. Serial No. 582,710.

To all whom it may concern:

Be it known that I, LAWRENCE WHITEMAN, a citizen of the United States, residing at Shinnston, in the county of Harrison and State of West Virginia, have invented certain new and useful Improvements in Floatless Carburetors, of which the following is a specification.

My said invention relates to a carburetor and it is an object of the invention to provide a carburetor which shall operate without the use of a float such as is commonly found in devices of this character.

A further object is to provide a carburetor the mixing chamber of which shall be supplied with both hot and cold air to be mingled with the gasoline or other liquid fuel.

Referring to the accompanying drawings which are made a part hereof and on which similar reference characters indicate similar parts,

Figure 1 is a side elevation of my device with parts broken away,

Figure 2 a plan, and

Figure 3 a detail of a part shown in the other figures.

In the drawings reference character 10 indicates the tubular body of the carburetor, having secured to one side thereof a receptacle for gasoline 11, here shown as tubular. The receptacle has an inlet pipe 12 adjacent its upper end and an outlet pipe 13 adjacent its lower end, the latter communicating with a fuel nozzle 14. At the lower end of the receptacle 11 is a plug 11^a by means of which the contents of the receptacle may be drained off. This plug finds its use in draining off water which is sometimes mixed with gasoline and which in this device will settle at the bottom of the receptacle below the opening into outlet pipe 13 and is thus prevented from gaining access to the mixing chamber.

The fuel nozzle 14 comprises a lower enlarged portion having a threaded extension 15 adapted to engage threads on the body 10 and a central cavity opening through the top of the fuel nozzle and being enlarged below the extension 15. At the lower end of the valve a cock 16 is attached having a handle 17 by operation of which the valve may be drained.

A needle valve 18 is slidably located in the upper wall of the body 10 and is normally positioned to close the fuel passage in the nozzle 14. The needle valve is supported on

a lever 19 and is normally held by means of a spring 20 in a position to close the opening in the nozzle 14, said lever 19 having at its free end a roller 21. This roller co-acts with a cam surface on a lever 22 mounted on the shaft 23 carrying a butterfly valve 24 which serves as a throttle. The cam portion of the lever is best shown in Figure 3 and comprises a downwardly inclined portion 25 of the lever and a leaf spring 26 secured thereto at one end as by a screw 27 and adjustably spaced therefrom at the other end by set-screw 28. In this manner the inclination of the leaf spring may be changed 65 and thus the operation of the needle valve 70 will also be varied.

At one side of the carburetor is an inlet pipe 29 having threaded connection to the body 10 and having side openings at 30 and 31 leading to a central passage through which cold air passes to the mixing chamber in the body 10. A pipe 32 serves to conduct hot air into the mixing chamber adjacent its opposite end, this pipe being here shown as 75 connected to the end closure of the body 10. The air for pipe 32 may be heated by the exhaust gases of the engine.

In the operation of my device the needle is normally held in position to close the 85 valve by means of the spring 20 as shown in Figure 1. When the engine is to be operated the throttle is opened to an extent predetermined according to the desired speed and rotation of the shaft 23 causes the cam 26 to 90 depress the adjacent end of lever 19 and raise the needle 18 to a sufficient extent to admit the necessary amount of fuel. The greater the degree to which the throttle is opened the further also will the needle be 95 withdrawn to admit additional fuel and vice versa.

Having thus fully described my said invention, what I claim as new and desire to secure by Letters Patent, is:

A carburetor comprising a body, a fuel nozzle in said body, a fuel inlet and fuel reservoir communicating therewith, an inlet for air into the body adjacent said nozzle, a throttle valve in said body, a needle valve for closing the fuel nozzle, a lever on said body pivotally supported intermediate its ends and having one end connected to said needle valve for operating the same, 105 spring means associated with said lever normally forcing the needle valve against its seat, said lever having its free end provided 110

with an offset portion, a roller on said offset portion, an operating arm for said throttle valve having an extension normally overlying the roller on said lever for pressing said roller toward said body against the action of said spring means for raising the needle valve from its seat, an adjustable cam plate carried on the underside of said extension for varying the angle of the inclined 10 surface of the operating extension, and a set screw extending through said operating

extension into engagement with said cam plate to vary the opening movement of the needle valve relative to the opening movement of the throttle valve, substantially as 15 set forth.

In witness whereof, I have hereunto set my hand at Clarksburg, West Virginia, this 10th day of July, A. D. nineteen hundred and twenty-two.

LAWRENCE WHITEMAN.
